DESIGN FOR A DRESS

Nettie Rosenstein, New York, N. Y.

Application January 2, 1941, Serial No. 97,766

Term of patent 3½ years

To all whom it may concern:

Be it known that I, Nettie Rosenstein, citizen of the United States, residing at 101 Central Park West, New York city, in the county of New York and State of New York, have invented a new, original, and ornamental Design for a Dress, of which the following is a specification, reference being had to the accompanying drawing, forming part thereof.

I claim:

The ornamental design for a dress, substantially as shown.

NETTIE ROSENSTEIN.
